UNITED STATES PATENT OFFICE.

JOHN W. MORWAY, OF BRISTOL, CONNECTICUT, ASSIGNOR TO THE E. INGRAHAM COMPANY, OF BRISTOL, CONNECTICUT, A CORPORATION.

INTERMITTENT-ALARM CLOCK.

No. 831,233.

Specification of Letters Patent.

Patented Sept. 18, 1908.

Application filed June 19, 1905. Serial No. 265,881.

To all whom it may concern:

Be it known that I, JOHN W. MORWAY, a citizen of the United States, residing at Bristol, in the county of Hartford and State of Connecticut, have invented a new and useful Improvement in Intermittent-Alarm Clocks; and I do hereby declare the following, when taken in connection with the accompanying drawings and the characters of reference marked thereon, to be a full, clear, and exact description of the same, and which said drawings constitute part of this specification, and represent, in—

Figure 1, a view in front elevation of an intermittent-alarm-clock movement constructed in accordance with my invention, the front plate of the movement being removed; Fig. 2, a plan view of the movement; Fig. 3, a broken view in vertical section on the line *a b* of Fig. 2 looking in the direction of the arrow *c*; Fig. 4, a detached broken perspective view of the crown escapement-wheel, showing the yielding intermittent-alarm pin carried by it; Fig. 5, a perspective view of the intermittent-alarm star-wheel.

My invention relates to an improvement in "intermittent-alarm clocks," so called because the alarm instead of being sounded continuously is interrupted periodically until the spring runs down or the alarm is shut off, the object being to produce at a low cost for manufacture a simple and reliable mechanism constructed with particular reference to fewness of parts and economy of space.

With these ends in view my invention consists in mechanism having certain details of construction and combinations of parts, as will be hereinafter described, and pointed out in the claims.

In carrying out my invention as herein shown I mount a three-pointed star-wheel 2 so as to turn freely upon a let-off arbor 3, journaled in the usual manner in the front and rear movement-plates 4 and 5 and furnished at its rear end with a finger-button 6, by means of which it is manually turned in one direction or the other for "setting" the alarm. The star-wheel 2 carries a pinion 7, meshed into by the third wheel 8 of the time-train, whereby the wheel 2 is driven in the direction of the arrow *d* on Fig. 1. A pinion 9 on the arbor 10 of the third wheel 8 meshes into the second wheel 11, which is mounted

on the center arbor 12, carrying a pinion 13, 55 meshing into the first wheel 14, which is mounted on the mainspring-arbor 15 and carries a pawl 16, engaging with the teeth of a ratchet-wheel 17, secured to the said arbor 15, upon which the mainspring 18 is wound 60 and to which the inner end of the said spring is secured. The third wheel 8 also meshes into a pinion 19 on the arbor 20 of the fourth wheel 21, which meshes into a pinion 22 on the arbor 23 of the pallet-wheel 24, the teeth 65 of which are engaged by a pallet 25 on the arbor 26, on which the escape-lever 27 is also mounted, the same coacting with a pin 28, carried by the balance-wheel 29, the escapement of which is controlled by a hair-spring 70 30. This train may be of any other approved construction; but however constructed and however arranged it will be employed to drive the star-wheel 2 in the direction of the arrow *d*.

The lower or inner edges of the long teeth of the star-wheel 2 coact with a yielding pin 31, formed by bending forward at a right angle one end of a coiled spring 32, the coil of which encircles the forward end of the arbor 80 33 of the crown escapement-wheel 34 of the alarm-train, the other end 35 of the spring being bent and passed through a hole 36 in the said wheel. The said arbor 33 carries a pinion 37, meshed into by a wheel 38, secured 85 to a pinion 39, mounted on the let-off arbor 3, so as to turn freely thereupon, this arbor being normally held against rotation by the friction of a spring 40, encircling its rear end and interposed between the rear movement- 90 plate 5 and a collet 41, fixed on the arbor.

At its forward end the let-off arbor 3 passes through a let-off spring 42 of ordinary construction and having its free end turned inward to form a finger 43 for engagement with a stop-wire 44, depending from the arbor 45, carrying the verge 46, which coacts with the wheel 34 and also carrying the hammer 47. The extreme forward end of the let-off arbor 3 is furnished with a let-off or alarm-cam pin 100 48, which rides upon the edge of a let-off or alarm-cam 49, carried by the minute-wheel 50, which is mounted upon the projecting forward end of the said arbor 3 and which meshes into a pinion 51, carried by the intermediate dial-work wheel 52, which meshes into a pinion 53 on the center arbor 12, which carries the minute-wheel 55, which meshes

into the pinion 51, the wheels 50, 52, and 55 forming what is commonly known as the "dial-work." The "shuck-pinion" 39 is engaged by the main wheel 56 of the alarm-train, this wheel being mounted upon an arbor 57, carrying the alarm-spring 58, which exerts under this arrangement a constant effort to revolve the escapement-wheel 34 in the direction of the arrow d' . A shut-off lever 59, arranged in position to be engaged by the pin 31, is mounted upon a shut-off arbor 60, arranged in close proximity to the verge-arbor 45.

In using my improved intermittent-alarm clock the same will be set in the usual manner by means of the finger-button 6. Then when the cam 49 "drops off," so to speak, the pin 48 the spring 42 disengages itself from the stop-wire 44. Now if the stop-lever 59 is turned to clear the pin 31 the alarm-train will be released and the alarm sounded until the time-train has brought one of the teeth of the star-wheel 2 into position to be engaged by the pin 31, by means of which the alarm-train will be arrested until the time-train has carried the said tooth of the star-wheel into a position where the pin 31 clears it. The alarm will then be sounded for the interval required for the time-train to rotate the star-wheel 2 sufficiently to bring its next succeeding tooth into position to be engaged by the pin 31, which will engage with the lower edge of the said tooth and stop the alarm-train until the time-train has cleared this tooth from the pin 31, and so the action of the clock will be continued until the spring 58 has run down or until the stop-lever 59 is thrown into the path of the pin by turning the arbor 60 by means of its finger-button 60^a.

I wish particularly to call attention to the fewness of new parts employed by me and also that during the sounding of the alarm the power of the alarm-spring 58 is virtually thrown upon the time-train for the reason that the power of the spring is constantly tending to turn the wheel 34, carrying the pin 31 in the direction of the arrow d' , the said pin being at the same time engaged with the under face of one of the teeth of the star-wheel 2, which is at the same time being actuated in rotation in the same direction by the time-train.

It is apparent that in carrying out my invention some changes from the construction herein shown and described may be made. I would therefore have it understood that I do not limit myself thereto, but hold myself at liberty to make such departures therefrom as fairly fall within the spirit and scope of my invention.

Having fully described my invention, what I claim as new, and desire to secure by Letters Patent, is—

1. In an intermittent-alarm clock, the combination with the time and alarm trains thereof, of a star-wheel in gear with the time-

train and constantly rotated thereby, and a pin rotated by the alarm-train for coaction with the said star-wheel by direct contact with the teeth thereof, whereby the alarm-train is periodically stopped and released by the successive engagement of the teeth of the star-wheel by the said pin. 70

2. In an intermittent-alarm clock, the combination with the time and alarm trains thereof, of a star-wheel in gear with the time-train and constantly rotated thereby, and a yielding pin rotated by the alarm-train for coaction with the said star-wheel, whereby the alarm-train is periodically stopped and released by the successive engagement of the teeth of the star-wheel by the said pin. 75

3. In an intermittent-alarm clock, the combination with the time and alarm-trains thereof, of a star-wheel in gear with the time-train and constantly rotated thereby, a pin 85 rotating with the arbor of the escapement-wheel of the alarm-train for coaction with the said star-wheel by direct contact with the teeth thereof, whereby the alarm-train is periodically stopped and released by the successive engagement of the teeth of the star-wheel by the said pin, and means to engage with the pin to shut off the alarm. 90

4. In an intermittent-alarm clock, the combination with the time and alarm trains thereof, of a star-wheel in gear with the time-train and constantly rotated thereby, and a yielding pin carried by the escapement-wheel of the alarm-train and coacting with the teeth of the said star-wheel. 95

5. In an intermittent-alarm clock, the combination with the time and alarm trains thereof, including a let-off arbor, of a star-wheel turning loosely on the said arbor and in gear with the time-train which constantly rotates it, and a pin rotated with the arbor of the escapement-wheel of the alarm-train and coacting by direct contact with the teeth of the said star-wheel by which the rotation of the pin and hence the actuation of the alarm-train is periodically interrupted. 105

6. In an intermittent-alarm clock, the combination with the time and alarm trains thereof, of a star-wheel continuously rotated by the time-train, and a pin carried by the alarm-train, coacting with the said star-wheel by the teeth of which it is periodically engaged and constantly under the tension of the spring of the alarm-train which tends to move it in the direction in which the star-wheel is being rotated by the time-train. 110

7. In an intermittent-alarm clock, the combination with the time and alarm trains thereof, of a star-wheel constantly driven by the time-train, a pin coacting with the said wheel and driven by the alarm-train, a shut-off arbor, and a shut-off lever mounted on the said arbor and arranged to be thrown into the path of the said pin for shutting off the alarm. 115

8. In an intermittent-alarm clock, the com- 130

bination with the time and alarm trains thereof, of a star-wheel constantly driven by the time-train, and a yielding pin applied to the escapement-wheel of the alarm-train and 5 formed by bending one end of a coiled spring the coil of which encircles the arbor of the said escapement-wheel and the other end of which is connected with the wheel itself.

9. In an intermittent-alarm clock, the combination with the time-train thereof, of a star-wheel driven continuously thereby, a 10 let-off arbor on which the said wheel turns loosely, and an alarm-train including a "shuck-pinion" mounted on the said arbor, 15 a main wheel meshing into the said pinion, a second wheel driven by the said pinion, an

escapement-wheel driven by the second wheel, and a pin carried by the escapement-wheel for coaction with the said star-wheel, the tension of the alarm-spring being constantly transmitted to the said pin and tending to turn the same in the direction in which the star-wheel is constantly turned by the time-train. 20

In testimony whereof I have signed this 25 specification in the presence of two subscribing witnesses.

JOHN W. MORWAY.
